UNITED STATES PATENT OFFICE.

PHILIP FRANCIS ODDIE, OF LONDON, ENGLAND, ASSIGNOR TO THE ODDESSE DAMPF PUMPEN GESELLSCHAFT MIT BESCHRÄNKTER HAFTUNG, OF HAMBURG, GERMANY.

DUPLEX DIRECT-ACTING PUMPING APPARATUS.

SPECIFICATION forming part of Letters Patent No. 624,854, dated May 9, 1899.

Application filed September 23, 1898. Serial No. 691,747. (No model.)

To all whom it may concern:

Be it known that I, PHILIP FRANCIS ODDIE, engineer, a subject of the Queen of Great Britain, residing at 9 Mansel road, Wimbledon, London, in the county of Surrey, England, have invented certain new and useful Improvements in Duplex Direct - Acting Pumping Apparatus, (for which an application for patent has been filed in Great Britain 5 March 1, 1898, No. 5,022, and in Germany April, 1898,) of which the following is a specification.

This invention relates to improvements in duplex direct-acting pumping apparatus, and is designed to enable such pumps to be worked by means of steam used "expansively"—that is to say, to enable the supply of steam to the piston-cylinders to be cut off considerably before those pistons have completed their 20 respective strokes, instead of the supply of steam, as is ordinarily the practice, being continued substantially to the end of each stroke.

In carrying out my invention I provide at the "water end" or part of the pump-chamber behind each plunger a separate or extra chamber, into which a prolongation or plunger extension from the end of the main pump-plunger enters through suitable bushing or packing, and the extra chamber of the one 30 (duplex) pump or main chamber is in communication with the rear or back end of the other pump or main chamber, while the extra chamber of the other pump or main chamber is in communication with the opposite main 35 chamber. No additional valves are required to enable the parts to operate, and other parts are substantially as usual.

In the drawings, Figure 1 represents a longitudinal section, and Fig. 2 a sectional plan, 40 of the water end of a duplex pump arranged to carry out my invention; Figs. 3, 4, 5, and 6, by four views in sectional plan, the sequence of motions performed by the steam-pistons and auxiliary or compensating plungers, so as to facilitate a correct comprehension 45 of the cycle of movements performed during one complete reciprocation of the operating parts, as shown in the drawings.

Behind each pump-cylinder (marked I and

II, respectively) is provided an auxiliary chamber a^3 or b^3 , in which an auxiliary piston or plunger a^2 or b^2 works, as the case may be, and which auxiliary plungers are respectively fastened to the respective pump pistons or plungers A^2 B^2 and pass through suitable bushes or packing a^4 b^4 into the auxiliary chambers a^3 b^3 . The auxiliary chamber a^3 of the one pump I is connected by means of a channel a^5 with the back end b of the other pump II, while the auxiliary chamber b^3 of the pump II is connected by a channel b^5 with the opposite end a of cylinder I. Thus no additional gear or valves are required and only those ordinarily in use are needed.

The steam enters either the steam-cylinder A or B and drives the piston A' or B' and piston-rod and with it sets in motion the pump-plunger A^2 or B^2 corresponding and an auxiliary plunger a^2 or b^2 .

The steam can be cut off at a suitable point, either fixed or variable—for example, two-thirds of its stroke. In the ordinary construction the pump-pistons A must come to rest as soon as the steam is cut off, as the effective steam-pressure is not strong enough to overcome the water-pressure in the pump. In the present invention, on the other hand, the main piston of the one is relieved at this moment by the motion of the auxiliary piston in the other.

In operation, referring to Fig. 4, the steam being admitted to what for the sake of distinction I will call "steam-cylinder" A, operating the steam-piston A' and rod or connection to operate its coacting plunger A^2 in the main pump portion in the direction of the arrow 1, such steam may be cut off at a convenient variable or predetermined point in the stroke—say, for instance, at a point about two-thirds of its stroke—the piston then assuming the position shown in Fig. 5.

In the ordinary construction the motion of the plunger A^2 would almost immediately upon steam being cut off come to rest at the point shown in Fig. 5 on account of the effective steam-pressure becoming insufficient to overcome the water-pressure.

In duplex pumping apparatus arranged ac-

ording to my invention while the steam-piston A' is acting upon the main plunger A² to pump water the plunger extension a² in its extra chamber a³ is meanwhile also forcing 5 water therefrom into the pump-valve chamber b behind main plunger B² until the steam-piston A' has reached two-thirds of its entire stroke and the pump-plunger A² the same extent. Then main plunger B², as already referred to and shown in Fig. 5, being operated 10 by steam-piston B' and its connection, commences its return motion in its pump-cylinder II, and in doing so the pressure in rear thereof being relieved the pressure in the extra 15 chamber a³ partakes of that relief, facilitating the completion by plunger A² of its stroke.

When the steam supplying pressure to piston B' is cut off upon it and its coacting main plunger B² having completed their strokes to 20 the extent of two-thirds the full stroke, a position indicated by Fig. 6, cut-off is effected and the stoppage of its stroke is prevented by the main plunger A² starting on its return stroke under the operation of its own steam- 25 piston A' and communicating the pressure of the water at its front end to the extra chamber b³ and additional plunger b², provided in like manner to the rear end of the main plunger B², the water-pressure passing by channel 30 b⁵, thereby assisting that plunger B² in its completion of the stroke. Then, referring to Fig. 3, the piston A' in the cylinder A continues its motion in the direction of the arrow 7, the steam is cut off, and the piston B' 35 commences its return motion in the direction of arrow 8. Until the piston A' reaches the position shown in this figure—about two-thirds of its stroke—the main plunger A² has been forcing water through the delivery-valve of the 40 pump, exercising the full area of its surface, and has at the opposite faces A⁴ of its main plunger and reduced face a⁶ of the auxiliary plunger been drawing water through the suction-valves, the combined areas of these two 45 faces A⁴ and a⁶ equaling approximately the area of the opposite face A³. As soon as the piston A' has reached the position indicated in this figure the piston B' commences its 50 traverse in the direction of arrow 8, and consequently the plunger B² and auxiliary plunger b² partake of the same motion. The motion of the plunger B² by its rear face B⁴ pressing on the water in b communicates that 55 pressure through channel a⁵ to the auxiliary chamber a³ in rear of auxiliary plunger a² and presses on the face a⁶ of that auxiliary plunger, assisting the piston A to complete the stroke. As soon as this has been accomplished the 60 piston B', (see Fig. 4,) still moving in the direction of the arrow 2, arrives at the point where its steam-supply is cut off and piston A' is about commencing its return traverse in the direction of arrow 1, and doing so, the water-pressure in front of plunger A² being 65 relieved, that relief of pressure is by the chan-

nel b⁵ communicated to the chamber b³ in rear of the auxiliary plunger b², and thereby the completion of the stroke of piston B' is assisted, and so on the cycle of operations is continued repeatedly, thereby constituting a 70 compensating arrangement by which the excess of pressure at the commencement of the stroke of the one steam-piston, as A', is through its coacting plunger, as B², utilized in aid of the deficiency of steam-pressure existing toward the end of the stroke of the opposite steam-piston, and so on. 75

Although I have referred to two-thirds cut-off, this extent of cut-off may be varied. Again, I have for illustration described the 80 extra chambers as being arranged in rear of the main plungers and chambers; but they may be arranged in other relative positions, as may be found most convenient under particular circumstances, and the extra or extension pump-plungers will be arranged in accordance with the change of position of their chambers. Such an arrangement of plungers and auxiliary plungers and their chambers may be conveniently used with arrangements of steam-cylinders used in what are known as the "compound type of duplex pumping-engines." 85

Having now particularly described and ascertained the nature of my said invention and in what manner the same is to be performed, I declare that what I claim is— 95

1. In a duplex pumping-engine the combination with the two steam-actuated pistons, as A' and B', and their connected plungers A² and B², of auxiliary plungers as a², b², respectively, auxiliary chambers therefor and water-passages a⁵ and b⁵ connecting the spaces between the suction and delivery valves of the main plungers with the opposite chambers 100 in rear of the auxiliary plungers respectively, substantially as shown and described.

2. In a duplex pumping-engine, a pair of main steam pistons and cylinders and connected main plungers and cylinders, an auxiliary plunger connected to the one face of one of the said main plungers, an auxiliary chamber in rear thereof, a connecting-channel connecting said auxiliary chamber with the space in rear of the other of the said main 110 plungers, a second auxiliary plunger connected with the other main plunger, a second auxiliary chamber therefor and a second connecting-channel connecting said second auxiliary chamber with the chamber of the first-mentioned main plunger, as set forth. 115

3. In a duplex pumping-engine, steam-pistons A' and B', coöperating main plungers A², B², auxiliary plungers a², b², and cylinders for the same to reciprocate in, in combination 125 with pressure-relieving passages connecting, respectively, the cylinder of one auxiliary plunger of one pump with the cylinder of a main plunger of the other pump, and arranged as described, whereby to permit the one 130

plunger to operate in relief of the other plunger toward the end of the stroke of the latter to enable said latter plunger to complete its stroke by the expansion of steam after steam-pressure thereto has been cut off, substantially as described.

5 In testimony whereof I have hereunto set

my hand in presence of two subscribing witnesses.

PHILIP FRANCIS ODDIE.
